RALPH H. BINNS, OF NEW YORK, N. Y.

CLOSURE LOCK.

Application filed August 19, 1922. Serial No. 582,853.

To all whom it may concern:

Be it known that I, RALPH H. BINNS, a citizen of the United States, and a resident of the city of New York, in the county of 5 New York and State of New York, have invented certain new and useful Improvements in Closure Locks, of which the following is a specification.

My invention relates to a lock, and is particularly intended for use in connection with a closure member of a type hereinafter set forth.

It is a well appreciated fact that one of the most efficient forms of closure is that 15 which employs two series of arms spaced one from the other, which arms are formed with headed portions adjacent their outer ends, an actuating member being provided which co-operates with the arms for causing 20 the headed ends of each series of the same to extend into the space existing between the bodies of the arms of the other series to thus interengage these arms, or which actuating member upon being properly moved will 25 cause a disengagement of the arms to thus open the closure.

However, objection has been noted to the use of a closure of this nature, in that the actuating member has often been accidentally moved when the arms are in closed position, so that the closure has been opened. Also in certain associations in which a closure of this nature is employed, a certain strain has been exerted upon the closure, 35 and this strain quite often causes the actuating member to move along the arms and effect a detachment of one series from the other of the same.

Having these and other difficulties in mind, 40 my present invention aims to provide a lock for a closure of this nature which lock will prevent any movement of the actuating member with respect to the arms other than upon said actuating member being deliberately moved.

A further object of my invention is that of providing a lock which is primarily intended for association with the actuating member, and which will require a deliberate 50 manipulation of its body in order to permit of a travel of the actuating member along the arms.

A still further object of the present invention is that of providing a device of the 55 character stated which will serve to exert a

locking influence upon the parts named, which influence will be in direct proportion to the separation strain exerted upon the closure parts.

Another object of my present invention 60 is that of providing a closure lock which may be substituted for the pull member commonly associated with the actuating member, it being noted that the lock, in addition to performing the functions aforementioned, 65 will also act as a pull member to enable the actuating member to be readily manipulated when it is desired.

Still another object of my invention is 70 that of providing a lock of the nature specified which will embody an extremely simple form of construction, and thus be free of mechanical difficulties, and which will also be capable of being placed upon the market at a nominal figure.

With these and further objects in mind 75 the present invention consists essentially of a locking element movably carried by the actuating member and adapted, when in operative position to engage the parts of the closure in such a manner as to prevent a movement of one of the same with respect to the other.

Reference is had to the attached sheet of 80 drawings as illustrating a practical embodiment of my invention. It will be seen in these drawings that;

Figure 1 is a front view of a conventional form of closure of the type afore-identified, together with an actuating member therefore, the latter being shown in the position assumed during the closing operation of the former, the latter carrying my improved lock.

Figure 2 is a view similar to Figure 1 but 95 showing the parts in their final or locked position.

Figures 3 and 4 are longitudinal sections taken along the lines 3-3 and 4-4 and in the direction of the arrows indicated in Figures 1 and 2 respectively, and

Figure 5 is an enlarged fragmentary view of a detail of construction hereinafter described.

It will be noted in these views that the conventional type of closure afore-referred to has been illustrated, and thus the reference numeral 6 indicates the strips or base portion, which each mount one series of arms 105 spaced one from the other and formed with 110

heads as at 8, it being understood that, as aforementioned, the heads of each series of arms extend into the space existing between the other series of arms, and are brought 5 into and removed from this position by means of the actuating member 9 moved along the closure proper, it being further noted that in accordance with conventional construction, this actuating member is provided with a rail 10 for the mounting and traversing of a pull member by means of which the actuating member is moved in the manner specified.

However, in lieu of the pull member commonly employed at this point, I provide an element which serves as a lock as well as a pull member, and this element includes a plate 11 which has its upper end bent as at 12 to provide a pair of inwardly extending arms 13 for slidable engagement with the rail 10. The plate is also preferably shaped to conform to the shape of the actuating member 9, and to thus present a neat appearance. A pair of fingers 14 are formed 25 integral with the plate 11, and are provided at points spaced from the arms 13, these fingers 14 being bent inwardly and downwardly and extending into a plane beyond that into which the arms 13 extend for a 30 purpose hereinafter specified. Finally it will be noted that the plate 11 (referring to its locked position as shown in Figures 2 and 4) has its lower end portion bent inwardly and also slightly upwardly as at 15, 35 and this end portion is of a length greater than the thickness of the lower outer edge of the actuating member 9.

In use it will be understood that the parts are normally in the position shown in Figures 2 and 4. In this position the fingers 40 14 bear against the stop members 16 provided one at the upper end of each of the series of arms 8. Obviously this will prevent any movement of the actuating member 45 along the arms of the closure, incident to the fact that the plate 11 is at the upper limit of its travel, along the rail 10. Also assuming that a pull is exerted upon the two series of arms in opposite directions, which would 50 normally cause a movement of the actuating member along the same, and a consequent opening of the closure, it will be appreciated that the stop member 16 will bear against the lower edges of the fingers 14 and tend to 55 push the same upwardly. This will cause the plate 11 to tend to rock around the arms 13 which will act as a pivot, and thus the lower end of the plate will be thrown inwardly and will have its outer edge firmly 60 engage the arms to thus preclude any movement of the actuating member with respect to the closure, and in fact it will be understood that the greater the tendency of the 65 arms to separate, the greater will be the thrust upwardly against the fingers 14, thus

consequently increasing the thrust inwardly on the part of the bent portion 15, and locking the parts more firmly.

The described operation of the device is due to the fact that the locking fingers 14 70 in the locked position shown in Figures 2 and 4 are presented in a plane beyond the plane including the axis of pivot arms 10, so that any upward pressure on locking fingers 14 causes the pivot plate 11 to tend to 75 press more closely against the face of actuating member 9 and interlocking members 7.

Assuming however that it is desired to move the actuating member 9 with respect to the arms to disengage the same, one from 80 the other, it will be understood that this may readily be accomplished by simply swinging the lower end of the plate 11 around the arms 13, which latter act as a pivot, thus causing the parts to assume the position 85 shown in Figures 1 and 3. The plate 11 may now be slid along the rail 10 until it reaches a point adjacent the lower end of the same, and a continued pull exerted upon the plate will cause the actuating member 9 to ride over the arms to effect an opening of the closure, it being obvious that when the parts of the closure are again to be engaged that a pull upon the plate 11, in an opposite direction will cause the same to ride along the rail 10 to a point adjacent the upper end of the actuating member 9, and this action, if continued, will cause the said actuating member to move along the closure to the position shown in Figures 2 and 4 subsequent to which the plate 11 may be swung to the position also shown in these figures.

Thus it will be understood that the objects of this invention have been accomplished 105 and it will be readily appreciated that numerous modifications of structure might readily be resorted to without in the least departing from the scope of my claims; which are—

1. In a closure lock, the combination with stringers carrying spaced interlocking members, and an actuating member embracing and sliding upon said interlocking members for effecting their engagement and disengagement, of a plate movably attached to said actuating member, and fingers upon said plate extending inwardly therefrom beyond said point of attachment and adapted to engage parts carried by said stringers. 115

2. In a closure lock, the combination with stringers carrying spaced interlocking members, and an actuating member embracing and sliding upon said interlocking members for effecting their engagement and disengagement, of a plate pivotally mounted upon said actuating member and movable into and out of parallel relation therewith, and locking fingers projecting inwardly from said plate 120 between its ends to a plane parallel with 125

said actuating member beyond that including the axis of said pivotal mounting, said fingers being adapted to engage parts carried by said stringers to prevent motion of 5 the actuating member thereon.

3. In a closure lock, the combination with stringers carrying spaced interlocking members, and an actuating member embracing and sliding upon said interlocking members for effecting their engagement and disengagement, of a plate having at one end arms which pivotally engage said actuating member, and between its ends inwardly presented locking fingers which extend inwardly 10 from said plate into a plane beyond that including the pivotal arms, said locking fingers being adapted to engage parts carried by said stringers to prevent motion 15 of said actuating member thereon.
4. In a closure lock, the combination with stringers carrying spaced interlocking members, and an actuating member embracing and sliding upon said interlocking members for effecting their engagement and disengagement, of a plate movably attached to 20 and shaped to fit over said actuating member and engage said interlocking members, and fingers carried by said plate between its ends adapted to engage parts carried by 25 30 said stringers.

5. In a closure lock, the combination with

stringers carrying spaced interlocking members, and an actuating member embracing and sliding upon said interlocking members for effecting their engagement and disengagement, of a plate movably attached at 35 one end to said actuating member and formed with inwardly presented fingers between its ends adapted to engage parts carried by said stringers, and an inturned portion 40 at its opposite end adapted to engage said interlocking members.

6. In a closure lock, the combination with stringers carrying spaced interlocking members, and an actuating member embracing and sliding upon said interlocking members for effecting their engagement and disengagement, of a plate pivotally attached 45 to said actuating member, locking fingers projecting inwardly from said plate into a plane beyond that including the pivotal attachment, said locking fingers being adapted to engage parts carried by said stringers, and a part projecting from said plate adapted to engage said interlocking 50 55 members when a thrust is exerted upon said locking fingers.

Signed at New York, in the county of New York and State of New York, this 18th day of August, A. D. 1922.

RALPH H. BINNS.
